FIG.5

BP

Technical drawing of a mechanical assembly, likely a transmission or gear box, showing various gears, shafts, and a flywheel. The drawing is labeled 'FIG.5' and 'BP'. The assembly includes a flywheel (147) with a ring gear (146, 149, 143, 148), a main shaft (15), and a gear assembly (23, 23, 188, 137, 135, 21, 133, 130, 120, 126, 129, 127, 128, 125, 141) mounted on a housing (144). Various gears and shafts are labeled with numbers such as 147, 146, 149, 143, 148, 188, 137, 135, 21, 133, 130, 120, 126, 129, 127, 128, 125, and 141.

Addressograph Company, Wilmington, Del., a
corporation of Delaware

Application May 8, 1931, Serial No. 535,818

24 Claims. (Cl. 101—47)

This invention relates to printing machines of the kind wherein bill sections such as utility bills, insurance notices and the like are printed.

In machines of this kind the bill sections to be printed are sometimes severed from a web and impressions are usually made on both faces thereof from permanent printing forms in the machine. Impressions are also made on the bill sections from the changeable printing devices which are sequentially passed through printing position in the machine. These changeable printing devices are filed in a predetermined sequence and are stored in drawers when not in use. When the machine is to be operated a plurality of these printing devices are introduced into a magazine in the machine from which magazine they are withdrawn and passed into printing position. Sometimes all of the printing devices passed through printing position are not to be used in a printing operation. However, in normal operation of the machine the successive passage of the bill sections and the sequential passage of the printing devices are in timed relation which must be maintained to insure proper operation and therefore if a printing device is not used in a printing operation upon movement into printing position the printing device feed mechanism must be operated in a normal manner while the operation of the other mechanism is interrupted.

The salient object of my invention is to interrupt the bill section feed when a printing device is not to be printed, and an ancillary object is to also interrupt the operation of other mechanisms in the machine operating on the bill sections whereby the aforesaid timed relation may be maintained.

The bill sections are severed from a continuous web withdrawn from a supply roll and another object is to move the web in a definite amount on each operation of the machine to insure proper movement of the web, proper sizing of the bill sections, and accurate orientation of the impressions on the bill section.

A further object of the invention is to perforate the web at transversely and longitudinally spaced intervals whereby properly located perforations will be provided on each of the bill sections.

A still further object of the invention is to provide a bill section safety and control device in connection with one of the printing couples including a permanent form from which impressions are made on the bill sections.

Other and further objects of the invention are to provide a machine which will be simple and

economical in construction and efficient and positive in operation.

In the selected embodiments of the invention illustrated in the accompanying drawings

Fig. 1 is a plan view, in which certain parts are broken away, of a printing machine embodying my invention; 5

Fig. 2 is a sectional detail view of a portion of the driving mechanism of the machine;

Fig. 3 is a transverse sectional view of a portion of the printing device feeding mechanism; 10

Fig. 4 is a transverse sectional view, drawn to an enlarged scale, illustrating the mechanisms employed to determine whether or not a printing device is to be used in a printing operation; 15

Fig. 5 is a fragmentary elevation of the right hand end of the machine as viewed in Fig. 1;

Fig. 6 is a fragmentary plan detail view of a portion of the perforating devices;

Fig. 7 is a vertical sectional detail view of the 20 perforating devices;

Fig. 8 is an elevational view, similar to Fig. 5, and including the positive web feed; Fig. 8a is a detail view of the web feeding mechanism;

Fig. 9 is a detail view of the positive web feed; 25

Fig. 10 is a fragmentary detail view of the positive web feed;

Fig. 11 is a sectional detail view taken substantially on the line 11—11 on Fig. 10;

Fig. 12 is a sectional detail view taken substantially on the line 12—12 on Fig. 10; 30

Fig. 13 is a fragmentary plan detail view, partly in elevation and partly in section, of a portion of the bill section safety and control device used with one of the printing couples; and 35

Fig. 14 is a front view, partly in elevation and partly in section, of the mechanism illustrated in Fig. 13.

In the accompanying drawings I have illustrated a printing machine of the kind disclosed 40 in my co-pending application, Serial No. 459,599, filed June 6, 1930. This machine includes a main frame 15 (Figs. 5 and 8) supported on legs 16 rested on a suitable support. Also rested on this support are standards, such as 17, (Fig. 8) on 45 which a supply roll of paper is rotatably supported, and a web W is led from the supply roll and is passed over a roller 18 carried by a frame 19 and in this manner a diabolo is provided to keep the web taut. The web W may be directed to a device for positively feeding the web to the printing machine, as will be described herein-after, and it may be directed to a perforating device whereby holes may be punched therein at spaced intervals longitudinally and transversely 50 55

thereof, and a mechanism for accomplishing this will likewise be described hereinafter. The web is led to a guide roller 20 (Figs. 5 and 8) rotatably mounted in the frame 21 from whence it may be directed through a suitable printing couple as described in my referred to co-pending application so that impressions may be made on one face thereof. In the embodiment of the invention illustrated in Fig. 1 the machine does not include such a printing couple and herein the web is directed to a guide roller 20'. After passing through the printing couple adjacent the roller 20 or after passing over the guide roller 20' the web is directed to a suitable feeding device, to be described, and then to a cutting mechanism 22 which severs sheets S from the web W, and these sheets are deposited on conveyor belts 23 (Figs. 1, 5 and 8) to be carried over the table 24 into position below the platen P. During this movement each sheet successively engages the stop fingers 26 which are sequentially moved into stopping position to thereby orient the sections of the sheet below the platen P, said platen making impressions on the sheet from printing devices D (Fig. 4). These printing devices are introduced into the magazine M, (Fig. 1) disposed rearwardly of the platen P, and are withdrawn from the magazine and moved in a step-by-step manner into printing position below the platen, after which the printing devices are discharged from printing position, in the manner well understood, to be collected in a galley G. After the sheet S has been stopped by the last of the stop fingers 26 and an impression has been made thereon, it is moved along by the belts 23 to a printing couple C mounted in the frame 27 and from this printing couple the sheets are discharged into a suitable receptacle. The printing couple C may be, for example, one of the type disclosed in the application of Curtis George Kranz, Serial No. 404,092, filed November 1, 1929, now Patent No. 1,955,814, patented April 24, 1934, but it is to be understood that any suitable printing couple may be used at this position. It is therefore apparent that a roll of paper may be mounted at one end of the machine and that a web may be led therefrom which may be directed to a printing couple wherein impressions will be made at spaced intervals on one face of the web. From this printing couple the web is directed to a severing device which divides the web into sheets, said severing device dividing the web intermediate the impressions made thereon by the printing couple so that these impressions will be neatly oriented on one face of each of the sheets. The severed sheets are then moved along into printing position below a platen which makes impressions from variable printing devices on the face of the sheet opposite that on which the impression was made from the previously described printing couple. Prior to the time the sheet is severed from the web it is scored which divides the sheet into a plurality of sections such as a main body and one or more stubs and the platen P operates to make an impression on each of these sections, the stop fingers 26 positioning the sheet to permit the impressions to be so located. After the platen has made an impression on each section of the sheet, the sheet then passes to a printing couple wherein an impression is made on the same face of the sheet as that on which impressions were made by the platen, and the sheets are then discharged into a suitable receptacle wherein they are collected.

75 The foregoing is illustrative of the manner in

which bill sections, such as utility bills, insurance notices and the like, may be printed to receive impressions on both faces or only on one face thereof and on the main body and the stubs thereof.

5 A step-by-step movement is imparted to the web to feed it through the severing device so that sheets of a predetermined width may be severed therefrom and such a step-by-step movement is imparted to the web both when it is directed about the roller 20 and through the printing couple and when it is directed about the roller 20' when no printing couple is provided. This means for feeding the web in a step-by-step manner is illustrated in detail in Fig. 8a and as shown therein the web is directed over a ledge 15' either directly from the roller 20' or from the printing couple BP and in the latter case when the printing couple BP is disengaged from the web, the web extends between the ledge 15' 10 and the roller 20. A shaft 16' is mounted below the ledge and a rocker 17' is mounted on this shaft. The rocker 17' carries a roller 18' and from the ledge 15' the web W is directed to the roller 18' so as to pass therebelow. A pair of 15 rollers 19' and 21' are mounted in the frame 21 in vertical alignment and after being passed below the roller 18' the web is directed between the rollers 19' and 21' to the cutting mechanism 22. The roller 19' is mounted on a shaft 23' at 20 the outer end of which there is a pinion 173 (Fig. 8) which meshes with a segment 172 on a rocker 171. A crank 24' is connected to the rocker 171 and is mounted on a shaft 25' which extends 25 across the frame 21 to receive a rotary movement 30 in the manner which will be described hereinafter and as this shaft is rotated, the crank 24' is reciprocated and likewise the rocker 171. A clutch 30' is interposed in the shaft 23' and operates so that the roller 19' is rotated only during the 35 upward movement of the segment 25' and in this way a step-by-step movement is imparted to the roller 19'. At the end of the shaft 23' opposite that carrying the pinion 173 is a gear 26' and meshing therewith is a gear 27' fast on the shaft 40 28' carrying the roller 21'. The step-by-step movement imparted to the shaft 23' is transmitted through the gears 26' and 27' to the shaft 28' to the roller 21' and therefore both the rollers 19' and 21' receive a step-by-step movement and 45 the magnitude of this movement is sufficient to feed the web the width of sheet to be severed therefrom and subsequently deposited on the tapes 23. The crank 24' is adjustable so that the width of the sheet may be varied and this adjustable crank is described in detail in my co-pending application, Serial No. 459,599, filed June 6, 1930.

50 In a machine of the above described type, impressions will be made by the platen from every 55 printing device passing therethrough, but this is not always desirable for it may not be necessary to make an impression from every printing device introduced into the magazine M. I have therefore provided a device whereby only determined of the printing devices will be used in a printing operation and the other printing devices will be passed through the machine without an impression being made therefrom. In an ordinary printing machine when certain of the 60 printing devices are not to be printed or, as it is termed, skipped, the platen is rendered inoperative. However, in the present machine wherein additional mechanisms are provided, such as two 65 additional printing couples, a web feeding mech- 70 75

anism, a severing device, and when used, a perforating device and a positive web feed, it is necessary that these additional mechanisms also be rendered inoperative.

5 The determination as to whether or not a printing device is to be used in a printing operation is brought about by a suitable selector device which includes a detecting member that acts on the printing devices withdrawn from the 10 magazine M, this usually being done on the printing device immediately behind the one in printing position, this location being known as selector position. The detecting member located at selector position acts on identifying means on the 15 printing device in this position and this identifying means may be in the form of tabs, openings or the like, located at predetermined positions on the printing devices so that when the detecting member of the selector acts thereon, the 20 printing device will be printed or skipped depending upon the set-up of the selector.

It is within the purview of my invention to provide a detecting member of approved form which 25 will operate a suitable selector device. I have, however, in the present instance, shown a detecting member and a selector device of the type described and claimed in the application of Walter T. Gollwitzer, Serial No. 497,438, filed November 22, 1930. This selector cooperates with the platen 30 operating shaft 28. The platen is carried by a rocker mounted on the frame 15 and includes branch arms carrying rollers embracing cams fast on a sleeve 28' disposed about the shaft 28. On the sleeve 28' is a lug 29 (Fig. 4) engaged by 35 the nose of a pawl 30 pivotally mounted at 31 on a disc 32 fast on the shaft 28, a spring 33 normally acting on the tail of the pawl to hold the nose thereof engaged with the lug. When the tail of the pawl is engaged, in the manner to be described, the nose is disconnected from the lug and consequently the sleeve 28' is disconnected from the shaft and the platen P is not operated. At this same time the other mechanisms in the machine, save the printing device feed mechanism 40 are rendered inoperative, and this is brought about by the cooperation of the detecting member 34 with the identifying means on the printing devices D. In the present instance this identifying means is in the form of tabs T and the detecting member has one or more pins 35 removably 45 mounted in selected openings therein to cooperate with tabs located at predetermined positions on the printing device to thereby determine the selection. Each time the printing device feeding 50 mechanisms are operated to move a new printing device into printing position the detecting member 34 is moved toward the tabs on the printing device D in selector position.

The printing device feed mechanism employed 55 herein is of the character described in the referred to application of Walter T. Gollwitzer, and this mechanism includes a rocker 36. The detecting member 34 is pivotally mounted on a rocker 38' mounted on the frame 15 at 37 and an arm on the rocker 36 engages the rocker 38' on each operation of the rocker 36 to move the pins 35 in 60 the detecting member toward the tabs on the printing device D in selector position, the manner in which this is brought about being clearly described in the referred to Gollwitzer application.

If one or more of the pins 35 engage a tab or 65 tabs T the movement of said detecting member is arrested but if the pins do not engage a tab, the detecting member moves into a position beyond 70 that in which it would have been stopped had the

tabs been engaged thereby. Consequently, this detecting member is stopped in what may be either an upper or lower position, the upper position being the one in which it is stopped when the pins engage a tab. As is described in the referred to Gollwitzer application, the stopping of the detector member in the upper position so locates the index segment 35' that the lug 36' will be held out of the notch 37' and this causes the latch pawl 38, pivotally mounted on the frame 15, to be 10 locked in such a position that the notched nose 39 on the plate 40, secured to the arm 41, will be latched in the notch 40' in the pawl 38. Should, however, the detector member move into the 15 lower position, this latching does not occur.

When the latching operation is brought about the throwout arm 42 connected to the arm 41 is disposed in such a position that the tail of the pawl 30 engages therewith to disengage the nose of the pawl from the lug 29 to thereby interrupt 20 operation of the platen. This also so positions the arm 43 that a clutch 44 in the driving mechanism is disengaged.

The shaft 28 is constantly rotated when the machine is in operation and this shaft is rotated 25 from the shaft 45, (Fig. 1) these shafts being interconnected through the bevel gears 46' and 47'. Rotatably mounted on the shaft 45 is a flywheel 46 to which power is supplied from a suitable source such as an electric motor, the flywheel 30 being connected to the shaft by the clutch 47. Since the shaft 28 is constantly operated, I provide a means for driving the printing device feed mechanism therefrom and this includes an eccentric 48 having a band 49 thereabout carrying 35 a connecting rod 50 extended through a sleeve 51 pivotally connected to the rocker 36. Mounted on the sleeve 51 is a pawl 52 engageable with a collar 53 fast on the connecting rod 50 and when the pawl engages said collar the sleeve 51 is attached 40 to the connecting rod to move therewith. It has been stated that the sheet embodies a number of sections and that impressions are made from the printing devices on each of these sections and therefore each printing device remains in printing 45 position until the platen has made the required number of impressions therefrom. In the present instance a three-section sheet is being printed and consequently each printing device remains in printing position until three impressions 50 have been made therefrom. This is accomplished by disconnecting the pawl 52 from the collar 53 during two operations of the platen operating 55 shaft 28. To accomplish this, a gear 54 fast on the shaft 28 meshes with a gear 55 fast on the shaft 56 suitably supported in the machine. The ratio between the gears 54 and 55 will be equal to the number of sections on the bill and hence in the present instance the ratio will be three to one so that the gear 54 will make three revolutions to one of the gear 55. Journalized in a bracket 60 57 is a shaft 58 and a universal connection 59 extends between the shafts 56 and 58. The shaft 58 makes but one revolution to three of the platen operating shaft. On the shaft 58 is a cam 60 engageable with a roller 61 on the arm 62 medially mounted at 63 on an arm 64 which is pivotally mounted at 65 on a lug 66 on the frame 15. A spring 67 interconnects the arms 62 and 64 and acts to urge the arm 62 into engagement with a 65 stop pin 68 on the arm 64 whereby these arms act as a unit. On the arm 64 is a cam face 69 engageable with a pin 70 on the pawl 52. Until the roller 61 is engaged by the cam 60, the cam face 69 70 engages the pin 70 and holds the pawl 52 out of 75

locking connection with collar 53 but when the cam 60 engages the roller 61 the arms are so moved that the pawl is permitted to lock the sleeve 51 to the connecting rod 58 whereupon the rocker 36 and the printing device feed are operated. Thus, when the ratio between the gears 54 and 55 is three to one the printing device feed will only be operated once to every three operations of the platen shaft, and consequently if the sleeve 10 28' is connected to the platen shaft the platen P will be operated to make three impressions on the sheets and the sheets will be oriented relative to the platen by the stop fingers 26. In Fig. 1 I have shown four stop fingers 26 but when a three section sheet is being printed only three of these stop fingers will be operated, the fourth stop finger being provided for use when a four-section sheet is to be printed and it is to be understood that a greater or less number might be provided. 15 20 It has been stated that the arm 43 is moved and held in a certain position when the notched nose 39 latches in the notch 40'. On this arm 43 there is a depending portion 71 (Fig. 2) carrying a roller 72 engageable with the roller 73 on the arm 74 pivotally mounted at 75. The arm 74 includes a throwout arm 76 and when the arm 43 is held in the position above described the throwout arm 76 is so disposed that it will engage the tail 77 of the pawl 78 of the clutch 44 to disengage the nose 79 of the pawl from the notch 80 in the collar 81 fast on the drive shaft 45. The pawl 78 is pivotally mounted on the gear 82 and when the nose 79 is disengaged from the notch 80, the movement of the gear 82 is interrupted. 25 30 The gear 82 meshes with a gear 83 fast on the shaft 84 which has a bevel gear 85 thereon (Fig. 1) that meshes with a bevel gear 86 on the cam shaft 87' which operates the cams that control the stop fingers 26. Also fast on the shaft 84 is a bevel gear 87 (Figs. 1 and 2) which meshes with a bevel gear 88, and this bevel gear 88 drives through a suitable gear train to operate the severing device 22. This gear train also operates the shaft 25' to drive the web feeding mechanism. 35 40 When a printing couple BP, such as that disclosed in Figs. 5 and 8, is used it is also driven from these intermeshing gears 87 and 88. Consequently, when the roller 72 acts on the roller 73 to position the throwout arm 76 in the path of the tail 77 of the pawl 78 to disconnect the nose 79 from the notch 80 operation of the cam shaft 87' is interrupted and operation of the printing couple BP is likewise interrupted. Operation of the severing device is also interrupted as well as the web feeding mechanism and operation of the conveyor belts 23 is also stopped, these belts being driven in the manner set forth in my previously referred to co-pending application. It is therefore apparent that when the clutch 44 is disengaged operation of the various mechanisms in the machine, save the shaft 28 and parts driven therefrom, is interrupted. The platen which is driven from the shaft 28 is not operated inasmuch as the sleeve 28' will be disconnected from the shaft 28 but the gears 54 and 55 will continue to operate. These gears drive the printing couple C which includes a permanent form that makes impressions on the same face of the sheets as that receiving impressions from the printing devices D. This printing couple however will not operate by reason of a safety device which prevents operation of the printing couple when no sheet is in position to be printed thereby.

This safety device cooperates with a printing couple C which includes an impression cylinder

89 (Fig. 14) having an electro-plate or other suitable printing form fast thereon and cooperating with this impression cylinder is a platen cylinder 90 having a blanket thereon. The cylinder 89 is mounted on a horizontal shaft which is driven from the vertical shaft 91 that has a bevel gear 92 thereon which meshes with a bevel gear 93 fast on the shaft 56 whereby the shaft 91 and consequently the cylinder 89 will be driven with the shaft 28. On the shaft carrying the cylinder 89 there is a spur gear (not shown) which meshes with a spur gear 94 fast on the shaft 95 journaled in the frame 96 pivotally mounted at 97, and this frame is raised and lowered to and from printing position, this being controlled from the cam 98 fast on the shaft 56 and riding on the cam 98 is a roller 99 which follows the cam to regulate the raising and lowering of the frame 96 and therefore the platen cylinder. On the frame 27 there is a shoulder 101 engageable with a shoulder 102 on the arm 103 connected to the shaft 104 having a roller 105 thereon. The shaft 104 is carried by the clamp frame 106 which is pivotally supported in a suitable manner and which embodies an arm 107 on which there is a roller 108 that engages the face cam 109 on the cam 98. A rise on the face cam acts on the roller 108 to pivot the clamp frame 106 and the shaft 104 to elevate the roller 105 at a predetermined time in the cycle of operation. In vertical alignment with the roller 105 is a peripherally grooved roller 110 and when no sheet S is in position below this roller and the roller 105 is permitted to move downwardly it will move into the peripheral grooves in the roller 110 to position the shoulder 102 below the shoulder 101 to prevent the frame 106 from being pivoted downwardly, for the gear 94 always meshes with the gear on the shaft carrying the impression cylinder 89, but since the impression cylinder cannot be lowered when the shoulders 102 and 101 are engaged no offsets will be formed on the blanket on the platen cylinder 90. When, however, a sheet is disposed below the roller 105, said roller is prevented from passing into the peripheral groove in the roller 110 and therefore the shoulder 102 is held from engagement with the shoulder 101. This permits the frame 96 to pivot downwardly and the platen cylinder will act to make an impression from the printing cylinder onto the sheet S which will have been released to pass between these cylinders and below the roller 105. The sheet S is stopped by the finger 111 carried on the arm 112 on the shaft 113 which includes an arm 114 having a roller 115 thereon riding on the face cam 116 fast on the shaft 56. The face cam 116 operates in timed relation with the cam 98 and acts to elevate the fingers 111 immediately following the time the shoulders 102 and 101 would be engaged so that a sheet may move between the cylinders 89 and 90. In order to insure movement of the sheet, a clamp roller 117 is provided which is carried by the frame 118 on which there is an arm carrying a roller 119 meshing with the periphery of the cam 116 and at the time the finger 111 is raised, the roller 117 is lowered to thereby clamp the sheet onto the pulley 117 to insure movement thereof between the cylinders 89 and 90. It is manifest that the foregoing arrangement includes but two cams which control the operation of the printing couple and when the selector functions to interrupt movement of the sheets and no sheet moves into position below the roller 105 it is apparent that the printing couple C does not function to make an impression. The particular operation of the printing couple

C is described and claimed in the co-pending application of Curtis George Kranz, Serial No. 404,092, filed November 1, 1929, to which reference may be made for the details of construction.

It has been pointed out that under certain conditions of operation it is desirable that the web be perforated and these perforations are to be spaced both longitudinally and transversely in the web W. To accomplish this, a bracket 120 (Fig. 5) is fast to the frame 21 and carries a strip 121 (Fig. 7) having a T-shaped slot 122 therein in which the head of clamp bolts 123 may be secured. The clamp bolts 123 serve to lock the bearings 124 in transversely adjusted positions on the strip 121. Another strip 125 is carried by the bracket 120 and has a slot 126 therein in which the heads of clamp bolts 127 may be arranged, these clamp bolts serving to retain bearings 128 in transversely adjusted positions on the strip 125. The bearings 124 and 128 are aligned in cooperating pairs and the female portion 129 of a perforating die is arranged in each of the bearings 128. The perforating plungers 130 of the dies are slidably mounted in the bearings 124 and are acted on by springs 131 to be urged away from the female portions 129. Journaled in the bracket 120 is a shaft 132 carrying fingers 133 which are aligned with the plungers 130. On the shaft 132 is an arm 134 to which the lower end of a link 135 is pivotally connected, said link having a yoke 136 at the opposite end thereof disposed about a shaft 137 in the printing couple BP, said shaft being the one which carries the platen cylinder. On this shaft is a cam 138 and a roller 139 on the link 135 engages on this cam when the plungers are to be operated. At other times the fingers 133 are held in the position illustrated in Fig. 7. However, at a predetermined time in the operation of the device the roller 139 is moved by the cam and acts through the link 135 to pivot the shaft 132 to thereby quickly move the fingers 133 to thus force the plungers 130 through the web W and into the female portions 129 of the dies to thereby perforate the web which is directed about rollers 140 and 141 in the bracket 120 and from the roller 141 the web is extended between the bearings 124 and 128 to a roller 142. From the roller 142 the web is directed about rollers 143 and 144. The rollers 143 and 144 are carried on a plate 145 which has end plates such as 146. On one of the end plates 146 is a stud 147 extending through an arcuate slot 148 in the plate 146 carried by the frame 21. By loosening the clamp stud 147 the end plate 146 may be moved into adjusted positions to thereby vary the space between the rollers 143 and 142 and by so doing the extent of the web between the rollers 141 and the printing couple may be varied and by so doing the position of the perforations relative to the impression may be varied.

A positive web feed for withdrawing it from the supply roll may be provided to reduce excessive tension in the web feeding means. The web W is directed from the supply roll about a roller 18 carried by the frame 19 to provide a diabolo. From the roller 18 the web is directed to a roller 150 (Fig. 8) and thence to a roller 151. From the roller 151 the web is directed about a spool 152 and from this spool the web is directed to the roller 20 to be passed through the machine as previously described. The spool 152 is thus arranged in a bight in the web W, said bight being defined between the rollers 151 and 20. A pair of arms, such as 153, are provided which support a trough 154 into and from which the spool 152

may move. The arms 153 are pivotally mounted at 155 on the standards 17, and when the spool 152 moves into the trough 154 the arms 153 are pivoted downwardly. Connected to one of the arms 153 is a rod 156 normally urged in an upward direction by the spring 157 extending between a clamp on the rod 156 and a spring anchor fast on the bracket on the frame 21. The upper end of the rod 156 is connected to a plate 158 rotatably supported about the shaft 159. On one face of the plate 158 are cam surfaces 162 and cooperating therewith are rollers 163 carried by the frame 21 adjacent the bearing 164 in which the shaft 159 is journaled. When the rod 156 is moved downwardly by reason of the seating of the spool 152 in the trough 154, the plate 158 is rotated about the shaft 158, a sleeve 165 being disposed between said plate and the shaft 159. As the plate is thus turned the cam surfaces 162 move over the rollers 163 and the plate 158 is thereby slid axially along the sleeve 165. Juxtaposed to the plate 158 is a ring 166 and a spring 167 is disposed about the sleeve 165 between the ring 166 and the plate 158 and normally urges the plate away from said ring. Carried on the shaft 159 is a roller 168 and the web is directed between this roller 168 and the roller 150. Thus, each time the shaft 159 is rotated the web will be advanced. In order to operate the roller 159 I provide an arm 169 which is pivotally mounted at 170. As described in my co-pending application, Serial No. 459,599, filed June 6, 1930, previously referred to, an arm 171, unitary with the arm 169, carries a segment 172 meshing with a pinion 173 which is alternately rotated in opposite directions to thereby impart a reciprocatory movement to the arm 171 and consequently the arm 169. On the arm 169 is a segment 172 meshing with a pinion 173 rotatably mounted on the shaft 159. Fast to the pinion 173 is a collar 174 including a depending arm 175 carrying a pawl 176 engageable with the ratchet wheel 177 fast to the shaft 159. Thus, upon movement of the segment 172 in one direction the pawl will seat in the teeth of the ratchet and consequently movement will be imparted to the shaft 159, but upon movement of the segment in the opposite direction the pawl will merely ride over the teeth of the ratchet and no movement will be imparted. At the time the spool 152 seats in the trough 154 the bight formed in the web W will be of proper size and no more paper is to be fed until the extent of this bight is reduced. Thus, when the spool seats in the trough to move the rod 156 downwardly, which causes the plate 158 to be moved along the sleeve 165 as has been described, the bevelled shoulder 178 will engage the boss 179 on the pawl 176 and will pivot this pawl downwardly out of engagement with the teeth on the ratchet 177 and therefore even though the arm 169 is reciprocated no movement will be imparted to the shaft 159 and consequently the roller 168. But as soon as the extent of the bight is reduced, the spool will move from the trough 154 and the spring 167 will move the rod 156 upwardly and the plate 158 will be permitted to move away from the ring 166 and the bevelled shoulder 178 will be disengaged from the boss 179 whereby the pawl may again seat in the ratchet and operation will be carried out as previously described.

In the foregoing I have described a printing machine to which a web may be directed from a supply roll and I have described how this web may be fed in a positive manner. I have also

described how the web may be perforated and how these perforations may be located at transversely and longitudinally adjusted positions in the web. Furthermore, I have described how 5 sheets may be severed from the web and passed through the machine below the platen to receive impressions from changeable printing devices moved into position below the platen. I have also set forth how a printing couple may be provided which will make impressions on one face 10 of the web and preferably this printing couple makes impressions on the face of the web opposite that receiving impressions from the changeable printing devices. I have also shown that a selector may be provided in the machine which 15 will function to render the just described mechanisms inoperative when a printing device that is to be skipped is moved into printing position, and I have shown how all of the foregoing mechanisms 20 may be rendered inoperative save the printing device feed mechanism. Moreover, I have described how the sheets may be passed to another printing couple after having received impressions from the changeable printing devices 25 and this printing couple is employed to make impressions on the same face of the sheets as that on which impressions are made from the changeable printing devices. Furthermore, I have shown how this printing couple may be rendered 30 inoperative when no sheet is in position to be printed thereby and manifestly this device will cooperate with the selector to prevent operation when the selector functions to stop the sequential passage of sheets through the machine.

35 While I have illustrated and described a preferred form of construction for carrying my invention into effect it is to be understood that this

from said web, a platen, means for carrying the sheets past the platen, means for stopping the sheets in position relative to said platen, means moving changeable printing devices into printing position below said platen whereby impressions 5 may be made from said printing devices on said sheets by said platen, and means for rendering said platen, sheet stopping means, sheet carrying means, severing means, and web moving means inoperative when predetermined of said printing 10 devices are moved into printing position.

4. In a printing machine including means for moving a web to the machine, means for perforating the web, means for severing sheets from the web, a platen, means for carrying sheets past 15 the platen, means for stopping the sheets in position below the platen, means for moving changeable printing devices into printing position below the platen whereby impressions may be made on the sheets from the printing devices by the platen, and means for rendering said platen, sheet stopping means, sheet carrying means, severing means, perforating means, and web moving means inoperative when predetermined of the printing devices move into print- 20 25 ing position in the machine.

5. In a printing machine, means for withdrawing a web from a supply roll in predetermined amounts, means for moving the web to the printing machine, means for severing sheets from the 30 web, a platen, means for carrying the sheets past the platen, means stopping the sheets in position below the platen, means moving changeable printing devices into printing position below the platen whereby impressions may be made on 35 the sheets from the printing devices by the

8. In a printing machine, a printing couple, means for moving a web through said printing couple whereby impressions may be made at spaced intervals thereon, means for severing sheets from the web intermediate the impressions, a platen, means for carrying the severed sheets into printing position below said platen, means for moving printing devices having identifying means thereon into said printing position whereby impressions may be made on said sheets from said printing devices, and means for rendering said sheet carrying means, platen, severing means, web moving means, and said printing couple inoperative when printing devices having predetermined identifying means thereon move into printing position.
9. In a printing machine including a printing couple, means for moving a web through said printing couple, means for severing sheets from the web intermediate impressions made thereon by said printing couple, a platen, means for carrying the severed sheets past the plate, means for stopping the sheets in printing position relative to said platen, means for moving changeable printing devices having identifying means thereon into printing position below the platen whereby said platen may make impressions on said sheets from said printing devices, and means for rendering said platen, sheet stopping means, sheet carrying means, severing means, web moving means, and printing couple inoperative when printing devices having predetermined identifying means thereon move into printing position.
10. In a printing machine for making impressions on bill sections comprising a main body and one or more stubs, the combination of printing means including a form for making an impression in each printing operation thereof on each bill section, impression means, means for moving changeable printing devices into printing position relative to the impression means whereby impressions may be made from said printing devices on one face of the main body and stubs of each bill section separately, and means for rendering the printing means and the impression means inoperative when predetermined printing devices move into printing position relative to said impression means.
11. In a printing machine for making impressions on bill sections comprising a main body and one or more stubs, the combination of printing means including a form for making an impression in each printing operation thereof on each bill section, impression means, means for moving changeable printing devices into printing position relative to the impression means whereby impressions may be made from said printing devices on one face of the main body and stubs of each bill section separately, means for separating the bill sections from each other, and means for rendering the printing means, the impression means and the separating means inoperative when predetermined printing devices move into printing position relative to said impression means.
12. In a printing machine for making impressions on bill sections comprising a main body and one or more stubs, the combination of printing means including a form for making an impression in each printing operation thereof on each bill section and adapted to feed the bill sections through the machine during the printing operations thereof, impression means, means for moving changeable printing devices into printing position relative to the impression means whereby impressions may be made from said printing devices on one face of the main body and stubs of each bill section separately, means operating in cooperation with the printing means for feeding the bill sections through the machine, and means for rendering the printing means, the impression means and the feeding means inoperative when predetermined printing devices move into printing position relative to said impression means.
13. In a printing machine which includes a printing couple for making impressions on bill sections after movement thereof through a printing position in the machine, and means for preventing a printing operation of the couple when a bill section is not fed thereto, the combination of printing means including a form for making an impression in each printing operation thereof on each bill section, impression means, means for moving changeable printing devices into printing position relative to the impression means whereby impressions may be made from said printing devices on one face of the main body and stubs of each bill section separately, and means for rendering the printing means and the impression means inoperative when predetermined printing devices move into printing position relative to said impression means.
14. In a printing machine which includes a printing couple for making impressions on bill sections after movement thereof through a printing position in the machine, and means for preventing a printing operation of the couple when a bill section is not fed thereto, the combination of printing means including a form for making an impression in each printing operation thereof on each bill section, impression means, means for moving changeable printing devices into printing position relative to the impression means whereby impressions may be made from said printing devices on one face of the main body and stubs of each bill section separately, and means for rendering the printing means and the impression means inoperative when predetermined printing devices move into printing position relative to said impression means.
15. In a printing machine which includes a printing couple for making impressions on bill sections after movement thereof through a printing position in the machine, and means for preventing a printing operation of the printing couple when a bill section is not moved thereto by the bill section feeding means of the printing machine, the combination of printing means including a form for making an impression in each printing operation thereof on each bill section and adapted to feed the bill sections through the machine during the printing operations thereof, impression means, means for moving changeable printing devices into printing position relative to the impression means whereby impressions may be made from said printing devices on one face of the main body and stubs of each bill section separately, means operating in cooperation with the printing means for feeding the bill sections through the machine, and means for rendering the printing means, the impression means and the feeding means inoperative when predetermined printing devices move into printing position relative to said impression means.
16. In a printing machine including means for

- moving a strip of paper therethrough, printing means, means for moving changeable printing devices into printing position relative to the printing means whereby impressions may be made from said printing devices on said strip of paper by said printing means, a printing couple for making impressions on said strip of paper, means for severing sheets from the strip of paper intermediate the impressions made thereon by said printing couple, and means for rendering said strip moving means, printing means, printing couple, and severing means inoperative when predetermined printing devices move into printing position relative to said printing means.
17. In a printing machine including means for moving a strip of paper therethrough, printing means, means for moving changeable printing devices into printing position relative to the printing means whereby impressions may be made from said printing devices on said strip of paper by said printing means, a printing couple for making impressions on said strip of paper, means for severing sheets from the strip of paper intermediate the impressions made thereon by said printing couple, means for forming a bight in said strip of paper, and means for rendering said strip moving means, printing means, printing couple, severing means, and bight forming means inoperative when predetermined printing devices move into printing position relative to said platen.
18. In a printing machine including means for moving a strip of paper therethrough, printing means, means for moving changeable printing devices having identifying means thereon through printing position relative to said printing means whereby said printing means may make impressions from said printing devices on said strip, a printing couple for making impressions on said strip, means for severing said strip intermediate the impressions made by said printing couple, and means controlled by the identifying means on said printing devices for rendering said strip moving means, printing means, printing couple, and said severing means inoperative when printing devices having predetermined identifying means thereon move into printing position.
19. In a printing machine including means for moving a web to the machine, means for perforating the web, means for severing sheets from the web, a platen, means for carrying the severed sheets past the platen, means for stopping the sheets in printing position below the platen, means for moving changeable printing devices having identifying means thereon into printing position whereby impressions may be made on the sheets from the printing devices by the platen, and means for rendering said platen, sheet stopping means, sheet carrying means, severing means, perforating means, and web moving means inoperative when printing devices having predetermined identifying means thereon move into printing position.
20. In a printing machine, means for withdrawing a web from a supply roll in predetermined amounts, means for moving the web to the printing machine, means for severing sheets from the web, a platen, means for carrying the severed sheets past the platen, means for stopping the sheets in printing position below the platen, means for moving changeable printing devices having identifying means thereon into printing position whereby impressions may be made on the sheets from the printing devices by the platen, and means for rendering said platen, sheet stopping means, sheet carrying means, severing means, perforating means, and web moving means inoperative when printing devices having predetermined identifying means thereon move into printing position.
21. In a machine which includes a printing couple for making impressions on a sheet after movement thereof through a printing position in the machine and means for preventing printing operation of the couple when no sheet is moved thereto, the combination of means for moving a web to the machine, means for severing sheets from the web, a platen at said printing position, means for carrying the severed sheets into printing position relative to the platen, means for moving changeable printing devices into printing position below the platen whereby impressions may be made on said sheets from said printing devices, and selector means for rendering said platen, sheet carrying means, severing means, and web moving means inoperative when predetermined of the printing devices move into printing position.
22. In a machine which includes a printing couple for making impressions on a sheet after movement thereof through a printing position in the machine and means for preventing printing operation of the couple when no sheet is moved thereto, the combination of means for moving a web to the machine, means for severing sheets from the web, a platen at said printing position, means for carrying the severed sheets into printing position relative to the platen, means for stopping the sheets in position below the platen, means for moving changeable printing devices into printing position below the platen whereby impressions may be made on said sheets from said printing devices, and selector means for rendering said platen, sheet stopping means, sheet carrying means, severing means, and web moving means inoperative when predetermined of the printing devices move into printing position.
23. In a machine which includes a printing couple for making impressions on a sheet after movement thereof through a printing position in the machine and means for preventing printing operation of the couple when no sheet is moved thereto, the combination of a second printing couple, means for moving a web through the second printing couple, means for severing sheets from the web intermediate impressions made thereon in the second printing couple, a platen, means for carrying the severed sheets past the platen, means for stopping the sheets in printing position relative to the platen, means for moving changeable printing devices having identifying means thereon into printing position below the platen whereby said platen may make impressions on said sheets from said printing devices, and selector means for rendering said platen, sheet stopping means, sheet carrying means, severing means, and web moving means inoperative when printing devices having predetermined identifying means thereon move into printing position.
24. In a machine which includes a printing couple for making impressions on a sheet after movement thereof through a printing position in the machine and means for preventing printing operation of the couple when no sheet is moved thereto, the combination of a second printing couple, means for moving a web through the second printing couple, a severing device for cut-

ting sheets from said web after passage thereof through the second printing couple, a platen, means for carrying the severed sheets past the platen, means for stopping said sheets in position relative to the platen, means for moving changeable printing devices into printing position below the platen whereby impressions may be made on the sheets from the printing devices by the platen, and selector means for rendering said platen, sheet carrying means, sheet stopping means, severing means, the second printing couple, and said web moving means inoperative when predetermined of the printing devices move into printing position.

EMMETT C. HARTLEY.
